UNITED STATES PATENT OFFICE.

JAMES G. SPECK, OF PHILADELPHIA, PENNSYLVANIA, ASSIGNOR TO BIGELOW
HARTFORD CARPET COMPANY, A CORPORATION OF MASSACHUSETTS.

DESIGN FOR A RUG.

• 54,468.

Specification for Design.

Patented Feb. 10, 1920.

Application filed August 27, 1919. Serial No. 320,324. Term of patent 3½ years.

To all whom it may concern:

Be it known that I, JAMES G. SPECK, a citizen of the United States, residing at Philadelphia, in the county of Philadelphia and State of Pennsylvania, have invented a new, original, and ornamental Design for a Rug, of which the following is a specification, reference being had to the accompanying drawing, forming part thereof.

The drawing illustrates a portion of a rug, showing my new design.

I claim:

The ornamental design for a rug, substantially as shown.

JAMES G. SPECK.
